SPINNER FISH LURE

Edward W. Wiswald, 1527 Meadowbrook,
Round Lake, Ill.

Filed May 23, 1963, Ser. No. 75,022

Term of patent 14 years

(Cl. D31—4)

FIG. 1 is a plan view of a spinner fish lure embodying my new design;

FIG. 2 is a side elevation thereof, as shown in FIG. 1;

FIG. 3 is a front end elevation thereof, as shown in FIG. 1; and

FIG. 4 is a plan view of a modified form of the spinner fish lure shown in FIG. 1;

FIG. 5 is a side elevation thereof, as shown in FIG. 4;

FIG. 6 is a front end elevation thereof as shown in FIG. 4.

The dominant features of my design reside in the portions shown in full lines.

I claim:

The ornamental design for a spinner fish lure, as shown and described.
